UNITED STATES PATENT OFFICE

166,673

AIRPLANE

Alexander Kartveli, Huntington, N. Y., assignor
to Republic Aviation Corporation, Farmingdale,
N.Y., a corporation of Delaware

Application June 16, 1950, Serial No. 10,584

Term of patent 14 years

(Cl. D71—1)

To all whom it may concern:

Be it known that Alexander Kartveli, a citizen of the United States and a resident of Huntington in the county of Suffolk and State of New York, has invented a new, original, and ornamental Design for an Airplane described and claimed in the following specification and shown in the accompanying drawings wherein:

Fig. 1 is a plan view of an airplane embodying my new design;

Fig. 2 is a side elevation thereof;

Fig. 3 is a front elevation thereof; and

Fig. 4 is a perspective view thereof taken from the front or nose end.

The particular features which characterize the present design are the cathedral angle of the wings and the disposition of the horizontal stabilizers normal to the vertical stabilizer together with the associated elements of the aircraft.

What is claimed is:

The ornamental design for an airplane, substantially as shown and described.

ALEXANDER KARTVELI.
